Inventor,

P. J. Stoll,
Ex. Job Abbott, ATTORNEY.

P. J. STOLL, OF MARSHALLSVILLE, OHIO.

Letters Patent No. 85,186, dated December 22, 1868.

IMPROVED HITCHING-STRAP BUCKLE.

The Schedule referred to in these Letters Patent and making part of the same.

To all whom it may concern:

Be it known that I, P. J. STOLL, of Marshallsville, in the county of Wayne, and State of Ohio, have invented new and useful Improvements in Buckles for Hitching-Straps; and I do hereby declare that the following is a full, clear, and exact description of my invention, reference being had to the accompanying drawings, forming a part of this specification, and to the letters of reference marked thereon, of which drawings—

Figure 1 is a side elevation of my improved buckle, showing its application to a hitching-strap.

Figure 2 is a plan of the same, with the end of the hitching-strap removed.

Figure 3 is a plan of the buckle taken separately from the hitching-strap.

The nature of my invention consists in the peculiar construction of a buckle, which can be readily attached to an ordinary hitching-strap, and which forms, when so attached, a convenient mode of securing the hitching-strap to the post-ring, or other object to which the strap is to be secured; the peculiar utility of my invention consisting in the facility with which my buckle can be attached to any strap without the aid of any tools, excepting a punch or penknife, its perfect security against being lost off when so attached, and the advantage of always fastening the strap in a secure manner, so that all danger of the untying of the strap by the movements of the animal which it is used to secure, which is no uncommon occurrence in the ordinary mode of tying the strap, is entirely obviated.

To enable others skilled in the art to make and use my invention, I will proceed to describe its construction and operation.

The frame of my buckle is made of iron, or any other suitable material, and consists of the outside frame A, of the form shown in fig. 3, and the cross-bars F and G, which are either cast with frame A, or secured in the position shown, in any suitable manner.

The loop C is secured to the lower end of the frame A, and serves to hold the end of the strap after it has been buckled.

The front tongue E is pivoted to the cross-bar G,

as shown, and has an end bearing on the front part of the frame A.

The middle tongues D D are pivoted to the cross-bar F, and have end bearings on the cross-bar G, on each side of the tongue E, as shown.

The rear tongue B is pivoted to the cross-bar F, between the tongues D D, and has an end bearing on the rear part of the frame A, under the loop C, which loop is so arranged, and is of such a height as to allow said tongue B to clear it in turning up.

The manner of using this buckle is readily seen.

The strap is passed up under the rear part of the frame A, and buckled into position by the two tongues D D, the part of the strap being above the cross-bars F and G, as seen in figs. 1 and 2.

From the tongues D D the hitching-strap is formed in the loop I, around the post or other object to which it is to be secured, and then passes up under the front part of the frame A, where it is buckled into position by the tongue E, the end of the strap K being passed under the loop C, as seen in fig. 1.

The tongues D D are of such size that they together shall have about the same strength as the tongue E, as they are both subjected to nearly the same strain, while the tongue B may be made quite light, as it has no severe strain brought on it, but serves to prevent the buckle from sliding down the strap when not in use, and unbuckling the tongues D D, thus allowing the buckle to drop off and be lost.

Having thus fully described my invention,

What I claim as new, and desire to secure by Letters Patent, is—

The within-described buckle, consisting of the frame A, with cross-bars F and G and loop C, the front tongue E, centre tongues D D, and rear retaining-tongue B, the several parts being constructed, combined, and arranged as and for the purpose herein specified.

As evidence that I claim the foregoing, I have hereunto set my hand, in the presence of two witnesses, this 8th day of October, A. D. 1868.

Witnesses:

HENRY WINGER,

D. J. BAER.

P. J. STOLL.
